(57) **CLAIM**

The ornamental design for a sequencer machine, as shown and described.

DESCRIPTION

FIG. 1 is a front, right perspective view of a sequencer machine, showing our new design;

FIG. 2 is a top, rear, left perspective view thereof;

FIG. 3 is a front elevation view thereof;

FIG. 4 is a right elevation view thereof;

FIG. 5 is a rear elevation view;

FIG. 6 is a left elevation view thereof;

FIG. 7 is a top plain view;

FIG. 8 is an enlarged view of detail “8” identified in FIG. 3; and,

FIG. 9 is an enlarged view of detail “9” identified in FIG. 5.

In the drawings, the equal-length broken lines depict portions of the sequencer machine and form no part of the claimed design. The dash-dot-dash broken lines define the limits of the enlarged portions shown. All broken lines form no part of the claim.
